UNITED STATES PATENT OFFICE.

ELMER F. BLISS, OF SCHENECTADY, NEW YORK, ASSIGNOR TO GENERAL ELECTRIC COMPANY, A CORPORATION OF NEW YORK.

BLOCK-SIGNAL SYSTEM.

No. 848,959.

Specification of Letters Patent.

Patented April 2, 1907.

Application filed September 19, 1906. Serial No. 335,209.

To all whom it may concern:

Be it known that I, ELMER F. BLISS, a citizen of the United States, residing at Schenectady, county of Schenectady, State of New York, have invented certain new and useful Improvements in Block-Signal Systems, of which the following is a specification.

My invention relates to block-signal systems for electric railways employing the rails as return-conductor for the power-current; and its object is to provide a novel arrangement of signal-circuits permitting the use of rails conductively continuous for all currents as distinguished from those systems in which inductive bonds or similar devices are employed to prevent the signal-current from one block passing into another block while allowing the power-current to pass.

My invention consists in making the rails conductively continuous for both power and signal currents and employing sources of high-frequency alternating current connected at intervals across the track-rails, adjacent sources being of different phase, with signal-controlling means connected between the sources responsive only to the resultant current from both adjacent sources, so that if either source fails the signal for the track-section between the sources will be put at "danger."

My invention further comprises a novel relay construction especially applicable where relays are connected in pairs across the rails, as in my present system.

My invention will best be understood by reference to the accompanying drawings, in which—

Figure 1 shows diagrammatically a block-signal system arranged in accordance with my invention. Fig. 2 is an explanatory diagram. Fig. 3 shows a side elevation of a pair of relays arranged in accordance with my invention, and Fig. 4 shows a plan view of the same in cross-section on the line 4-4 of Fig. 3.

Referring first to Fig. 1, A represents the track-rails of an electric railway, which are made conductively continuous for all currents throughout their length. B represents the third rail or other supply-conductor for the power-current, which is connected to one terminal of the power-generator C. This generator may supply either direct or low-frequency alternating current. Its other

terminal may be connected to the track-rails A through a differential choke-coil c. D represents a high-frequency three-phase generator, which supplies current for the signal-circuits through the three-phase line-wires d', d'', and d''. E', E'', &c., represent transformers which have their primaries connected to the line-wires and their secondaries to the track. Small resistances e' and e'' may be employed in the secondary circuits of the transformers in order to prevent an excessive flow of power-current through the secondary windings. It will be noted that adjacent transformers are supplied from different phases of the generator D. F' and F'' represent a pair of relays, which are shown as of the well-known induction type, each having one winding connected across the track through a resistance f for the purpose of limiting the flow of power-current through the relay-windings. The other winding of each relay is supplied independently of the rail-circuit from the line-wires, and it will be noticed that the two relays are connected to different line-wires. The relay F' has a winding connected to the same phase as transformer E', while the relay F'' has its corresponding winding connected to the same phase as the transformer E''. The two relays jointly control the signal G', their contacts being connected in series with the signal-operating mechanism and with each other.

The effect of the currents of different phase on the relays will be evident from a consideration of Fig. 2. In this figure if o' represents the phase of the current supplied to the rails by the transformer E' and if o'' represents the current supplied to the rails by the transformer E'', o' and o'' being one hundred and twenty degrees apart, then the current through the track-windings of the relays F' and F'' will be represented by o''' displaced sixty degrees from both o' and o''. Now if the current through the second winding of relay F' be also represented by the line o' and the current through the second winding of relay F'' by o'', then it will be seen that the resultant current o''' coacting with the current in each of the other two relay-windings, produces a torque in each relay due to the sixty degrees phase displacement. Now if either transformer should fail—as, for instance, be-

cause of a broken rail or because of being shunted by a train—one of the component currents in the rail will disappear and the current in the track-windings of the relays will be shifted into phase with the current in the second winding of one of the two relays. This relay will consequently drop its armature, allowing the signal G' to go to "danger," while the other relay still has its normal torque—that is, both relays are responsive simultaneously only to the resultant current from both transformers E' and E^2 , and one of them will drop its armature upon the failure of either of its transformers.

15 The operation of the system is then as follows: With a train at H moving in the direction of the arrow the rails will be short-circuited between the transformer E^4 and relay F^6 . The current flowing through the track-windings of the two relays consequently comes wholly from transformer E^3 , so that there is no phase displacement between the currents of the relay F^6 . This relay consequently drops its armature. The circuit of signal G^3 is consequently broken, and though relay F^6 still holds up its armature, due to the phase displacement of the currents in its windings, it will drop its armature some time before the train reaches it and will not pick up until the train has passed transformer E^3 , since with the train between the relays and transformer E^3 there is no phase displacement of the currents in the windings of relay F^6 . Signal G^3 is consequently at "danger" and will remain at "danger" until the train has passed transformer E^3 a sufficient distance to allow the voltage supplied by this transformer to the rails to rise to a great enough value to supply the necessary component current to the relay F^6 for moving it to closed-circuit position. Relay F^6 will have picked up its armature some time after the train has passed the relays. Shortly before the train H reaches transformer E^3 it will have pulled down the voltage of transformer E^3 sufficiently to put relay F^3 or F^4 , or both, at "danger." Signal G^2 will consequently go to "danger" a short time before signal G^3 clears. The amount of this overlap depends upon the regulation of the transformer impedance of the rails, and the resistance of the track-winding circuit of the relays, and by employing a high-frequency alternating current to which the rails offer a high impedance and by properly designing the transformers and relays this overlap may be made so small as to be of no importance in practical operation.

60 In place of employing a separate track-winding for each relay an economy in power and in material may be secured by employing a single track-winding common to both relays, as shown in Figs. 3 and 4. In these figures, I' and I^2 represent two pivoted conducting disks, which form the secondary

members of the relays and carry the relay-contacts. These contacts are connected in series, as has been heretofore explained. Two C-shaped cores J are placed on opposite sides of the two disks, with coils K on each core. These coils are connected in series or in parallel with each other and to the track, and thus form a single winding which is in inductive relation to both members I' and I^2 . The relay F' has a C-shaped core L' on each side of the cores J , and on each of these cores is placed a coil M' , which is supplied with current independently of the rail-circuit, the two coils being reversely connected, so as to produce a torque in the same direction. The relay F^2 is similarly arranged. With this construction the current induced in each disk by the single winding K cooperates with the current induced by the other winding of each relay, so as to produce the necessary torque. By employing a single winding economy of current and power is obtained.

Although I have shown a three-phase system for the signal-circuits in which the currents supplied to the rails by adjacent transformers are one hundred and twenty degrees out of phase, it is obvious that other numbers of phases in which adjacent sources differ in phase by a different angle may be employed. Consequently I do not desire to limit myself to the particular arrangement shown.

What I claim as new, and desire to secure by Letters Patent of the United States, is—

1. In combination with an electric railway having both rails conductively continuous for all currents, sources of alternating current connected across the track-rails at intervals, adjacent sources being of different phase, and signal-controlling means connected across the rails at points between the sources and responsive to control a signal only to current of the phase of the resultant current from both adjacent sources.

2. In combination with an electric railway having both rails conductively continuous for all currents, sources of alternating current connected across the track-rails at intervals, adjacent sources being of different phase, and signal-controlling relays arranged in pairs at points between the sources, each relay having two coaxing windings, one connected across the track-rails and traversed by the resultant current from both adjacent sources, and the other supplied independently of the rails with current of the proper phase for producing an effective torque in both relays simultaneously only in conjunction with said resultant current.

3. In combination with an electric railway having both rails conductively continuous for all currents, sources of alternating current connected across the track-rails at intervals, adjacent sources being of different phase, and signal-controlling relays connected across the track-rails in pairs at points be-

tween the sources, the relays being responsive simultaneously only to current of the phase of the resultant current from both adjacent sources.

5. In combination with an electric railway having both rails conductively continuous for all currents, two sources of high-frequency currents of different phase connected across the rails a distance apart, a block-signal for 10 the portion of track between said sources, and signal-controlling means connected across the rails at a point between said sources and arranged to put said signal at danger upon a failure of current from either of said sources.
15. 5. In combination with an electric railway having both rails conductively continuous for all currents, two sources of alternating currents of the same frequency but different phase connected across the rails a distance apart, two relays connected across the rails at a point between said sources responsive simultaneously only to the resultant current from both sources, and a signal controlled by the joint action of said relays.
20. 6. In combination with an electric railway having both rails conductively continuous for all currents, two sources of alternating currents of different phase connected across the rails a distance apart, and a signal-controlling relay of the inductive type having two coacting windings, one connected across the rails at a point between said sources and the other supplied independently of the rails with current of the same phase as that supplied by one of said sources to the rails.
25. 7. In combination with an electric railway having both rails conductively continuous for all currents, two sources of alternating currents of different phase connected across the rails a distance apart, two relays of the inductive type each having two coacting windings, one winding of both relays being connected across the rails at a point between said sources, and the other windings of the 30 relays being supplied independently of the rails with currents corresponding in phase to the currents supplied to the rails by said two

sources respectively, and a signal controlled by the joint action of the two relays.

8. In an electric railway employing the 50 rails as return-conductor for the power-current, a pair of relays having a common winding connected across the track-rails and each having a second winding supplied with current independently of the rail-circuit and of 55 each other.

9. In an electric railway employing the rails as return-conductor for the power-current, a pair of relays having a common winding connected across the track-rails and each 60 having a second winding supplied with current independently of the rail-circuit and of each other, and a signal controlled by said relays jointly.

10. In an electric railway employing the 65 rails as return-conductor for the power-current, a source of alternating current connected to the track-rails, a pair of relays each comprising a short-circuited conducting member, a winding connected across the 70 track-rails in inductive relation to both members, and an independent winding for each relay coacting with the track-winding and supplied with alternating current independently of the rail-circuit.

11. In an electric railway employing the 75 rails as return-conductor for the power-current, a source of alternating current connected to the track-rails, a pair of relays each comprising a short-circuited conducting member, a winding connected across the track-rails in inductive relation to both members, an independent winding for each relay coacting with the track-winding and supplied with alternating current independently of 80 the rail-circuit, and a signal controlled by 85 said relays jointly.

In witness whereof I have hereunto set my hand this 18th day of September, 1906.

ELMER F. BLISS.
